UNITED STATES PATENT OFFICE.

FRANK A. HEADSON, OF MILWAUKEE, WISCONSIN.

PAPER-MAKING MACHINE.

Application filed November 15, 1920. Serial No. 424,216.

To all whom it may concern:

Be it known that I, FRANK A. HEADSON, a citizen of the United States, and resident of Milwaukee, in the county of Milwaukee and State of Wisconsin, have invented certain new and useful Improvements in Paper-Making Machines, of which the following is a specification.

This invention relates to that class of paper making machines in which paper pulp or material for forming the paper is deposited on an endless apron of felt or similar material, in a moist condition, and the water and moisture then removed by passing the layer of pulp or web of material to be operated upon, and the endless apron or felt upon which the pulp is deposited, between pressing rolls to remove the water from the pulp or web, and then causing the web to pass between and in contact with the peripheries of a series of drying rolls suitably heated for the purpose, so that the web or sheet of paper pulp is built up or formed while the pulp is in a moist condition, the water pressed out from the web of pulp, and the web or sheet of paper dried in one continuous operation.

The principal object of the invention is to provide a paper making machine of the class described, with web-forming and water-removing pressing roll mechanism adapted to form and press the water from a web or sheet of paper pulp or fibrous material to be operated upon, in a simple, uniform, economical and efficient manner, and in such a manner as to require a smaller number of pairs of water-removing pressing rolls than is found necessary in common practice in machines in which the ordinary and well known forms of water-removing pressing rolls are employed, and to enable the web of paper pulp or material operated upon to be more thoroughly and uniformly dried before passing to the main pressing and drying rolls than is commonly the case when ordinary known forms of water-removing pressing rolls or wringer rolls are employed.

A further object of the invention is to provide, in a paper making machine, a plurality of pairs of water-removing pressing rolls of such construction as to enable the water to be pressed out from the web of paper pulp in such a manner that the speed of operation of the machine may be increased to any desired suitable speed without causing any injury to the web or sheet of

pulp as it passes between the water-removing pressing rolls, and without causing any undesirable washing away of the pulp as the web of pulp passes between the pressing rolls for removing the water from the web, and whereby each successive pair of water-removing pressing rolls will admit the web of pulp therebetween in substantially as dry a condition throughout every portion of the web as the web was in when discharged from between the next preceding pair of rolls, instead of causing water to be constantly collected or dammed up in front of each pair of rolls so as to supersaturate every part of the web of pulp as it enters between the rolls when both the bottom and top rolls are solid are imperforate or of the form ordinarily employed.

Other and further objects of the invention will appear from the following description and claims, and from an inspection of the accompanying drawings, which are made a part hereof.

The invention consists in the features, combinations, details of construction, and arrangement of parts herein described and claimed.

In the accompanying drawings, Figure 1 is a diagrammatic view in side elevation of the forward or "wet" portion of a paper making machine provided with a plurality of pairs of water-removing pressing rolls constructed in accordance with my invention;

Fig. 2, is an enlarged detail view in elevation of a pair of water-removing pressing rolls constructed in accordance with my invention, taken transversely of the machine on line 2-2 of Fig. 1, with parts of the lower roll broken away, to show its construction, and with parts of the machine frame broken away or omitted; and

Fig. 3, is an enlarged detail view in transverse section, through a portion of the lower roll shown in Fig. 2, and a plurality of which are shown in Fig. 1.

In constructing a paper making machine in accordance with my invention I provide a paper-making machine 1, having a frame 105 2, which may be of any desired ordinary and well known form.

The machine which is shown in part, diagrammatically in Fig. 1, comprises in its construction a series of tanks or vats 3, each 110 of which is adapted to contain ground wood pulp or paper pulp floating in and complete-

ly saturated by a suitable quantity of water or liquid contained in the vats or receptacles 3. And rotatively mounted in suitable bearings, and operatively connected with suitable driving mechanism which may be of any desired ordinary and well known form, is a series, or any desired number of pulp carrying and depositing rolls 4, one for each tank or receptacle 3. Each of these 5 rolls 4 is rotatively mounted inside of its corresponding vat or tank 3 with its axle 5 in transverse relation to the tank. And each of said rolls is in the ordinary and well known form of a hollow cylinder having its 10 periphery formed of perforated or reticulated, or open-work material. Each of the 15 rolls 4 is normally partially submerged in a liquid mixture of wood or paper pulp floating in and saturated by a suitable quantity 20 or proportion of water contained in the tank in which such roll is rotatively mounted, and is adapted to raise upon the upwardly moving side of such roll, a layer of 25 wet pulp which is lifted up out of the water and deposited on the bottom or adjacent surface of an endless apron 6 formed of felt or similar material, said apron being supported by means of a series of idler rolls or feeding and supporting rolls 7 in position 30 to travel across and in position to receive a layer or web of wet paper pulp on the bottom side of the felt apron as the latter passes over and in position to be pressed against the paper-pulp depositing 35 peripheries of said rolls or molds 4. Mounted above and in parallel relation to each roll 4 is the usual corresponding pressing or web-packing roll 8 having an imperforate or solid peripheral body adapted to engage the 40 upper side of the lower lap of the endless apron or felt 6 as the latter passes over the rolls 4 and between each pair of rolls 4 and 8, so as to press the endless apron of felt 45 against the layer of paper pulp carried up to the apron by the roll or rolls 4, to be deposited on the lower side of the apron.

The tanks 3, rolls 4 and 8, and mechanism for operating the same, may be of any ordinary and well known or suitable form 50 familiar to those skilled in the art, and it is therefore deemed unnecessary to further describe the same in detail herein.

Mounted, by preference, over the tanks 3, and in position to admit the upper lap of 55 the endless felt apron 6, and the web of wet paper pulp deposited on and carried by said apron or felt, between the adjacent peripheries, is a plurality of pairs of water-removing pressing rolls 9, 10, for pressing 60 the water from the web of pulp or paper and from the endless apron 6 and the similar endless upper apron 11 of felt, as said endless aprons 6 and 11, with the web of paper pulp 12 deposited in a thin web of uniform 65 thickness therebetween, pass between said

upper rolls 9 and lower rolls 10, toward and into position to pass between the usual series of heated drying rolls—not shown. The upper endless apron 11 of felt is supported in the usual manner throughout the length of 70 its upper lap by rolls 13 journaled in suitable bearings in the frame, and which may be of any desired ordinary and well known form.

The lower roll 10 of each pair of water-removing pressing rolls is, by preference, provided with a perforated or open-work outer cylindrical body portion or peripheral covering of reticulated material 14 formed of woven wire of fine mesh, laid upon and 75 covering an inner layer of perforated or reticulated material 15, formed of woven wire of coarser mesh than said outer layer 14. And the body or frame of each roll 10, of which the peripheral layers of perforated 80 or reticulated material 14, 15, form the outer peripheral covering or felt-engaging peripheries, is by preference, in the form of an open-work built up frame constructed as follows:

Circular end frames or webs 16 having radial spokes or spider arms 17 on and extending outward radially from hubs 18, are fixed to a supporting axle or shaft 19, the opposite ends or journal portions of which 95 are journaled in suitable bearings in side frame members 2, 2, as shown in Fig. 2. Intermediate or inner spiders 20, each consisting, by preference, of a series of radial arms or spokes 21 on and extending outward 100 radially from a central hub fixed to the shaft 19, are mounted upon and in fixed relation to the axle or shaft 19, at suitable intervals between the end frames or spiders 16.

A series of metallic—preferably brass— 105 rods 22 are mounted upon the outer peripheries of the spiders 16 and 20, in position to extend in parallel relation to each other and lengthwise of the roll, said rods or bars 22 being spaced apart at regular or uniform 110 distances from each other, and forming a longitudinally ribbed cylinder or longitudinally ribbed cylindrical frame.

Around the cylindrical ribbed frame-work formed by the rods 22 thus mounted on the 115 spiders 16 and 20, is wound spirally a rod or wire 23 of suitable dimensions in cross-section, and with its coils suitably spaced apart to form a suitable support for the outer peripheral layers of reticulated material 14 and 15, and permit water squeezed or pressed from the paper pulp or web of paper, and from the layers of felt formed by the endless aprons 6 and 11, between which the web of paper pulp is compressed 120 as the aprons and the web pass between the rolls, and the water is pressed from the web and felt through the reticulated, or perforated peripheral body portion of the cylindrical roll and inward toward the axial 125 130

center of the openwork or built up roll, to pass out through the bottom side and ends thereof into a trough or box-like receptacle 24 located beneath each pair of rolls 9 and 10, respectively.

The top roll 9 of each pair of said rolls, may be in the form of a solid cylinder of any suitable material, preferably provided with an outer cylindrical peripheral covering 25 of rubber.

Each of the troughs 24 is mounted beneath and in position to receive any water or liquid passing through or from the corresponding openwork or built up roll 10, 15 and is provided with one or more suitable discharge passages 26 which may lead back to any tank 3 or other receptacle. The troughs 24 may be mounted in the machine frame and supported in operative position 20 by any suitable support, such, for instance, as a bracket 27 or similar supporting member, mounted on or projecting from the end wall of each trough and supported by an adjacent frame member or trough support 25 28 located at opposite ends of each trough.

In a machine constructed in accordance with my invention as above described and shown, it will be readily seen that the wet pulp is carried up from the vats 3, by the rolls 30 4 and deposited on the felt or endless apron 6 in the ordinary and well known manner. The rolls 4—commonly called molds—may be of the same or similar construction to that of the rolls 10; but it is plain from the 35 foregoing description that the functions and mode of operation of the rolls 10 is not to carry on the surface thereof wet pulp to be deposited on the endless apron, but to coact with the rolls 9 to press from the wet 40 pulp already deposited on the endless apron as much of the water contained in the endless web of pulp as possible as the web of pulp is caused to pass between the perforated or openwork peripheries of the pressing 45 rolls 10 and the upper pressing rolls 9. The web of paper pulp 12 deposited on the endless apron of felt 6 is thus carried between the endless aprons 6 and 11, and caused to pass with said aprons or endless belts be- 50 tween the pairs of rolls 9 and 10, so that each pair of the rolls 9 and 10 receives the web of paper pulp in as dry a condition as possible, and presses out as much of the water contained in the pulp as possible, and water 55 is prevented, so far as possible, from being dammed up in front of or on the receiving side of the respective pairs of rolls 9 and 10. Instead of being dammed up in front of each pair of said rolls 9 and 10—as in the 60 case of using two imperforate or solid rolls such as are in common use, in lieu of a lower roll provided with a perforated or openwork periphery—it is plain that the lower rolls 10 constructed in accordance with this in- 65 vention and having perforated peripheries

against which the endless belt or apron of felt is pressed, permits the water contained in the web of paper pulp to be pressed through the lower endless apron of felt 6 and through the perforated or openwork periphery of the lower roll 10 of each pair of the above described pressing rolls, so that the water is caused to pass freely through the rolls 10 and into the troughs, to be carried to a suitable container or back to the tanks 3, as desired. It is plain that the speed at which the web of pulp is carried between the rolls 9 and 10 may be much greater than would be practicable with bottom rolls having imperforate peripheries 70 which would cause a piling up or damming of the water in the web of pulp and endless aprons on the receiving sides of the rolls. By thus causing the web of paper pulp to enter between each pair of pressing rolls in as dry a condition as possible, and causing all parts of the web of paper pulp to be in a dryer condition on entering between each pair of said rolls than it was on entering 75 between the preceding pair, the speed of 80 operation of the entire machine may be increased to a greater extent than would be practicable with ordinary pressing rolls in which both the top and bottom rolls have 85 imperforate peripheries. 90

I claim:—

1. In a paper making machine, the combination of a pair of water-removing pressing rolls rotatively mounted in parallel relation and comprising an upper roll, and a lower roll having a cylindrical periphery formed of woven wire fabric adapted to admit water through the openings in the periphery to the interior of the roll; an endless traveling apron mounted in position to pass 100 between said rolls and over and in engagement with the openwork periphery of the lower roll, and means for depositing a layer of wet pulp upon the surface of such endless apron in position to pass between the rolls, 105 said endless apron being located between the pulp and the periphery of the lower roll, and the pulp being out of contact with the openwork periphery of said lower roll. 110

2. In a paper making machine, the combination of a pair of water-removing pressing rolls rotatively mounted in parallel relation and consisting of an upper roll, and a lower hollow roll having a cylindrical periphery formed of openwork material comprising a series of longitudinal bars mounted in parallel relation upon supporting frame members and spaced apart, and an outer peripheral layer of reticulated material encircling said longitudinal bars, all 115 adapted to admit water through the openings in the periphery to the interior of the roll, an endless traveling apron having its upper lap mounted in position to pass between said rolls and between the openwork 120 125

periphery of the lower roll and a layer of paper pulp to be carried upon the endless apron but out of contact with the openwork periphery of the lower roll, and means for 5 operating said rolls and apron.

3. In a paper making machine, the combination of a pair of water-removing pressing rolls rotatively mounted in parallel relation and consisting of an upper roll 10 having an imperforate periphery, and a lower hollow roll having a periphery formed of openwork material comprising a series of parallel longitudinal bars spaced apart and mounted upon supporting frame members, an outer peripheral layer of reticulated material, and a flexible element wound around said longitudinal bars and forming an openwork support for said outer peripheral layer of reticulated material, all adapted to admit water through the openings therein to the interior of the roll, and a paper-pulp-carrying endless traveling apron adapted to pass between said rolls and between the openwork periphery of the lower 25 roll and a web of paper pulp carried upon said apron and out of contact with the openwork periphery of the lower roll.

4. In a paper making machine, the combination of a pair of water-removing pressing rolls rotatively mounted in parallel relation and consisting of an upper roll, and a lower roll having a periphery formed of openwork material comprising a series of longitudinal bars spaced apart and mounted upon supporting frame members, a spiral member wound around said longitudinal bars and having its spiral windings spaced apart, and an outer peripheral layer of woven wire encircling said spiral member 30 and supported thereby, all adapted to admit water through the openings in such periphery to the interior of such lower roll, a paper-pulp-carrying endless traveling apron mounted in position to pass between said rolls and between the openwork periphery of the lower roll and a web of wet paper pulp to be carried upon said apron and out of contact with the openwork periphery of the lower roll, and an upper endless 35 apron mounted in position to engage and pass between the web of paper pulp and the surface of the upper roll.

5. In a paper making machine, the combination of a pair of water-removing press-

ing rolls rotatively mounted in parallel relation and consisting of an upper roll, and a lower roll having a periphery formed of reticulated metal adapted to admit water through the openings in such periphery to the interior of the lower roll, a paper-pulp-carrying endless traveling apron formed of fibrous material mounted in position to pass between said rolls and between the openwork periphery of the lower roll and a layer of wet paper pulp to be carried upon said apron and out of contact with the openwork periphery of the lower roll, means for depositing a layer or web of wet paper pulp upon the surface of such endless apron in position to pass between the rolls and out of contact with the openwork periphery of the lower roll, and an upper endless apron mounted in position to engage and pass between the web of paper pulp and the surface of the upper roll.

6. In a paper making machine, the combination of a pair of water-removing pressing rolls rotatively mounted in parallel relation and consisting of an upper imperforate roll, and a lower roll having a periphery formed of reticulated material adapted to admit water through the openings in such periphery to the interior of the lower roll, a paper-pulp-carrying endless traveling apron formed of fibrous material mounted in position to pass between said rolls and between the openwork periphery of the lower roll and a layer of paper pulp to be carried upon said apron and out of contact with the openwork periphery of the lower roll, means for depositing a web of wet paper pulp upon the outer surface of such endless apron in position to pass between the rolls and out of contact with the openwork periphery of the lower roll, an upper endless apron having its lower lap mounted in position to engage and pass between the web of paper pulp and the surface of the upper roll, a water receptacle located in position to receive water discharged from the lower roll, and means for operating the rolls and aprons.

Signed at Chicago, Cook County, Illinois, October 27, 1920.
